DESIGN FOR A TOILET POWDER CONTAINER

Gaston Taieb, New York, N. Y.

Application October 19, 1935, Serial No. 59,129

Term of patent 14 years

To all whom it may concern:

Be it known that I, Gaston Taieb, a citizen of France, residing at 69 East 57th Street, in the city, county, and State of New York, and doing business at 439 Madison Avenue, in said city, have invented a new, original, and ornamental Design for a Toilet Powder Container, of which the following is a specification, reference being had to the accompanying drawing, forming a part thereof.

Fig. 1 is a perspective view of a toilet powder container in closed position showing my new design.

Fig. 2 is a perspective view thereof in opened position.

I claim:—

The ornamental design for a toilet powder container substantially as shown and described.

GASTON TAIEB.
